SOLID-FUEL-BURNING SPACE HEATER
WITH MAGAZINE AUTOMATIC DAMPERS AND HOT-AIR JACKET

De Witt H. Wyatt, Columbus, Ohio

Application November 14, 1945, Serial No. 628,443

6 Claims. (Cl. 126—68)

1

This invention relates to space heaters and, more particularly, to heaters or stoves of the solid fuel-burning type, having especial reference to room heaters employing vertical magazines in which coal, or other solid fuel, is introduced and fed gravitationally to combustion grates.

It is an object of the invention to provide a coal-burning space heater with improved means for supplying combustion air under regulable flow to the grate structure and fuel combustion zone of the heater, whereby to vary automatically and control the rate of fuel combustion in accordance with change in weather conditions or the heat requirements in the room or rooms heated by the heater.

Another object of the invention is to provide a space heater in which the hot gases of combustion, following their generation and release from the burning fuel, are caused to flow in intimate contact and heat-exchanging relationship with the heat-conducting walls of a multiplicity of vertically extending channels provided in a heat-transferring radiator arranged within the outer casing of the heater, room air being introduced into the bottom of the casing and confined for flow over the outer surfaces of the radiator, whereby to heat the room air prior to its release through outlets provided therefor in the top of the heater casing.

A further object is to provide a heater of this character with a thermostatically regulated by-pass valve which, when opened, diverts the hot flue gases from their normal travel through the radiator channels and allows such gases to pass, in full or in part, directly into the associated outlet flue of the heater, whereby to promote initial combustion of the fuel and effect rapid heating of the outlet flue and its associated chimney, so that normal circulation of the flue gases under changing draft conditions may be quickly and readily established.

Still, a further object is to provide such a heater with a plurality of room air-admitting passages having swinging and balanced dampers responsive to flue or chimney drafts, the said dampers opening or closing automatically as the draft increases or decreases, whereby to provide for increased or diminished air flow through said passages and automatically controlling the rate of fuel combustion and the maintenance of uniform temperatures and room areas under the influence of the heater.

In connection with the foregoing objects, I have worked out a number of novel structural details and part arrangements which will be more thor-

oughly understood by reference to the following description and the accompanying drawings, wherein:

Fig. 1 is a vertical sectional view taken through a coal-burning space heater formed in accordance with the present invention;

Fig. 2 is a similar view on a plane perpendicular to that of Fig. 1, as indicated by the line 2—2 of Fig. 1;

Fig. 3 is a horizontal sectional view on the line 3—3 of Fig. 1;

Fig. 4 is a similar view on the line 4—4 of Fig. 1;

Fig. 5 is a detail sectional view disclosing the by-pass valve and its associated thermostatic controls;

Fig. 6 is a rear elevational view of the mechanism disclosed in Fig. 5;

Fig. 7 is a detail vertical sectional view taken through the thermostatic control for the by-pass valve on the line 7—7 of Fig. 5;

Fig. 8 is a vertical sectional view through the thermostatic bellows having a user's adjustment;

Fig. 9 is a perspective view disclosing the exterior appearance of my improved space heater.

Referring more particularly to the drawings, my improved heater comprises a casing structure, indicated in its entirety by the numeral 10, of any suitable external configuration, such as the substantially cubical design disclosed in Fig. 9. The casing structure includes a base 11 having mounted thereon guides 12 for the slidable support of an ash receptacle 13. Also formed with the base is an air-admitting grille 14, by which air drawn from the floor is admitted into the casing structure for heating purposes. The front of the base is formed with an opening for the slidable reception of the receptacle 13. At the rear of the casing structure, the base is formed with a water-receiving chamber 15, accessible by a hinged lid 16, said chamber being adapted to receive a body of water which, under the operation of the heater, is vaporized to control the humidity of the warmed air.

Supported on the base is an inner casing or radiator 17, the latter being formed at its bottom with a horizontal flange 18 upon which is positioned a grate ring 19. Rotatable on the ring 19 is a metallic or ceramic grate member 20. This member is substantially hollow and has its walls formed with openings for the passage of air therethrough drawn from the ash pit 21. The grate member, in this instance, is formed with a spider 22 having projecting ends which receive rollers 23 by which the grate member is rotatably

supported on the ring 19. Rotatably supported in the ash pit is a shaft 24 having an exteriorly disposed handle 25. By means of said handle, the shaft 24 may be rotated or oscillated to impart turning movement to the grate member 20.

Surrounding the inner casing or radiator 17 and spaced from the walls thereof is an outer casing 26, forming a component part of the general casing structure. The front wall of the casing 26 is provided with a vertical series of louver openings 27, by which room air may be admitted into the air-heating passages 28 formed between the walls of the inner and outer casings. Adjacent to the openings 27, the front wall of the inner casing is formed with an opening 29, which is normally closed by a pivotally movable weight-balanced damper 30. When the heater is in active operation, and responding to chimney draft, the damper 30 swings inwardly, providing for air flow through the passage 31 of the inner casing into the ash pit 21 and thence through the grate member.

It will be understood that the openings in the grille 14 admit air into the passages 28 provided between the inner and outer casing units, but do not freely admit air into the ash pit, except through the operation of the barometric damper 30. Disposed centrally within the casing structure above the grate ring 19 is a refractory fire bowl 32, solid fuel being admitted into this bowl by way of the removable lid 33 formed in the central top portion of the outer casing 26. The bowl forms the lower part of a fuel magazine which possesses fuel storage capacity, so that the heater may operate for sustained periods of time without fuel replenishment. As the coal descends gravitationally through the fuel magazine toward the grate member, its temperature is progressively increased until active flame-producing combustion is present. The refractory elements 32 from which the fire bowl is formed are provided at intervals with slots 34 by which a secondary supply of air is admitted into the fuel contained within the fire bowl to effect active combustion thereof and minimize smoke formation, and also, to supply sufficient air to sustain combustion when the passages through the grate member are obstructed by ash accumulations.

Exteriorly, the fire bowl is surrounded by an air-confining casing 35 which communicates with a passage 36, formed in the inner casing 17 adjacent to the passage 31 (see Fig. 1). To admit room air into the passage 36, the front wall of the inner casing is formed with an opening 37 arranged in registration with the louver openings 27. A pivotally mounted weighted damper 38 normally closes the opening 37, but when the heater is in operation, the damper 38 swings to an open position providing for the flow of air through the passages 36 and into the casing 35 and thence through the slots 34 of the fire bowl to promote fuel combustion within the latter.

Above the fire bowl 32, the walls of the inner casing 17 effect the support of a head ring or shield 39 preferably formed from a ceramic or other refractory material. The opening in the center of the ring 39 receives the lower end of a magazine throat 40, which depends from the horizontal top wall 41 of the inner casing. The upper portion of the throat 40 includes an annulus 42 which is carried by the horizontal top wall 43 of the outer casing, the annulus 42 receiving the removable lid or closure element 33.

The inner casing at its top is also formed with a partition 44 which is arranged above the head

ring 39 and forms an air chamber 45. This chamber is in communication with a vertical passage 46 formed by the walls of the inner casing. Air from the louver openings 27 or the air heating space 28 is drawn into the passage 46 through an opening 47 which is controlled by a pivoted and weight-balanced damper 48. Thus, when the heater is in operation, and responding to chimney draft, the damper 48 opens to admit air into the passage 46 and thence into the chamber 45, the air passing from said chamber through a plurality of slots 49 formed in the head ring 39. This tertiary supply of air is commingled with the volatiles or smoke released from the distilling fuel, producing combustion thereof and minimizing smoke formation. It will be understood that the dampers 30, 38 and 48 are provided with adjustable weights 50 so that their response to given draft conditions may be readily regulated.

20 The gaseous products of combustion pass outwardly through the open top of the fire bowl 32 and, under normal conditions, flow downwardly, as indicated by the arrows A in Fig. 2, through passages 51 formed between the bowl and its surrounding casing 35 and the inner circular walls 52 of the inner casing. At its lower end, the passage 51 is in open communication with the lower ends of a plurality of flue passages or channels 53 formed by the corrugated walls 54 of the inner casing elements. (See Figs. 2 and 3.) The flue gases pass upwardly through the passages 53, as indicated by the arrows B, and enter an outlet chamber 55 formed in the top of the casing structure and which communicates with a flue outlet 56 leading to an outlet stack or chimney. The hot gases during their travel through the passages 53 heat the corrugated walls 54 so that the latter, in turn, may be employed in heating the room air flowing through the passages 28.

40 It will be understood that the room air is drawn into the heater through the openings in the grille 14 and through thermal circulation moves upwardly into contact with the outer surfaces of the corrugated walls 54 and, following such heating, escapes through openings 57 provided in the top of the outer casing. By corrugating the wall 54, its surface area is increased whereby to provide improved heat transfer between the heated gaseous products of combustion and the room air undergoing heating thereby.

45 In certain stages of operation of the heater, as when combustion is being initiated therein and chimney drafts are negligible, it is desirable to by-pass the passages 53 so that the gaseous products of fuel combustion may flow directly from the bowl to the flue gas outlet. To accomplish this, the inner casing is provided with a by-pass opening 58 in registration with the top of the fire bowl. This opening is normally closed by an automatically actuated damper or by-pass valve 59. The latter opens or closes the opening 58 with a quickly executed snap action, and such opening or closing is automatically accomplished in accordance with the temperature of the flue gases passing from the heater to the chimney. The valve or damper 59 is carried by the outer end of the longer arm of the bell crank lever 60, which is pivotally mounted as at 61 on a stationary support. The shorter arm of the bell crank lever is pivotally connected as at 62 with an arm 63, the latter being supported intermediately of its length by a pivoted link element 64. The outer end of the arm 63 is movably associated with the damper-actuating stem 65 of an adjustable

thermostatic unit 66 adaptable for user adjustment.

This unit comprises, as shown in Fig. 8, a housing 67, which is seated on an upper wall 68 of the heater casing contiguous to the flue gas outlet thereof, the housing being accessible exteriorly of the heating casing. Disposed within the casing and positioned on the upper surface of the wall 68 are gaskets 69 and a bottom plate 70, said gaskets and plate being disposed over an opening 71 formed in the wall 68. Said plate and gaskets are formed with axial openings 72 for the slidable reception of a thermostatic well element 73. This element is formed with heat-absorbing fins 74 which are arranged in the path of flue gases immediately prior to the discharge of the same from the heater.

The element 73 includes an axially disposed cavity 75 for the reception of a low boiling point liquid. Above the plate 70, the element 73 terminates in an enlarged head 76 with which is connected the lower end of a bellows 77. The upper end of the bellows is connected with a vertically adjustable disk 78, the latter having its periphery slotted as at 79, to receive the shanks of screws 80, the latter projecting upwardly from the head 76 and having their threaded ends received within openings formed in the housing 67. The disk is formed with an upwardly projecting threaded stud 81, which is receivable within an internally threaded bore 82 provided in a thimble 83, which is rotatably journaled in the upper portion of the housing 67. Connected as at 84 with the thimble 83 is a thermostat-adjusting knob 85. The lower edge of this knob is formed with an indexing pointer 86, which is movable with respect to an indicia-bearing strip 87, stationarily inserted in the exterior wall of the housing 67.

By turning the knob 85, either to the right or left, corresponding vertical movement will be imparted to the disk 78, thereby governing the response of the bellows 77 to internal pressures created by the vaporization of the liquid contained within the cavity 75 of the element 73. If the temperature of the flue gases leaving the heater is too high for a given setting of the knob 85, the internal gas pressure within the bellows will cause the head 76 to assume its extreme downward position, as shown in Fig. 8. Such downward movement of the element 73 produces accompanying movement of the associated stem 65.

As shown more particularly in Figs. 5 and 7, the lower end of the stem 65 is threaded as at 90 and positioned in an opening formed in the top of a bail 91. Lock nuts 92 are received on the threads of the stem to maintain the bail in desired positions of adjustment. The bail is formed with a pair of cross webs 93 which carry vertically aligned adjustable set screws 94 between which the outer end of the lever 63 is positioned.

The extreme lower end of the stem 65 is provided with an adjustable conically pointed bearing element 95 which is received in a depression 96 provided in the horizontal arm 97 of a substantially T-shaped lever 98, the latter being fulcrumed for movement about a horizontal pin 99 carried by a removable panel 100.

Above the pivot pin 99, the vertical arm of the lever 98 is formed with a depression 101 for the reception of the pointed end of a movable bellows stem 102, the latter being actuated by a thermostatic room-temperature bellows 103,

which is mounted in a casing 104 detachably connected as at 105 to the back wall of the heater casing.

The lower part of the vertical arm of the lever 98 is formed with a depression 106, which receives the pointed end of a spring-pressed stem 107. This stem is formed with a collar for engagement with one end of a coil spring 108, the other end of said spring engaging with a seating block 109, which is slidably adjustable in a socket 110 formed in the casing 104. A set screw 111 may be used for controlling the positions of the block 109 and the tension-exerting force of the spring 108, thus balancing the action of the bellows 77 of the user's thermostatic control as desired.

The link 64 is formed with a depression 112 with which engages the pointed inner end of a stem 113, the latter projecting rigidly from one side of a frame 114 which surrounds the bail 91. The opposite side of the frame 114 is formed with a squared shank 115 which is slidably received in a correspondingly formed opening provided in the panel 100, and is formed with a collar which acts as a seat for one end of a coil spring 116. The opposite end of this spring engages with an adjustable seating block 117, which is slidable in a socket 118 formed in the casing 104 below the block 109. An externally accessible set screw 119 is carried by the casing 104 for controlling the adjustment of the block 117 and the tension of the associated spring 116.

The lower end of the bail 91 is disposed adjacent to and immediately over the free end of an arm 120 which is carried by a check damper 121, the latter being pivoted as at 122 and adjustably weighted as at 123 so that normally the damper 121 arrests air flow through an opening 124 formed at one end of the air-conducting passage 125 leading from the ash pit 21. When the bail 91 descends under the action of the adjustable user's control 66 and the room temperature thermostat 103, the check damper 121 is opened to admit of air flow directly from the ash pit, or below the grate 20, into the waste gas outlet of the heater. The room temperature bellows 103 is connected by means of a capillary tube 126 and the bulb 127 adapted for the reception of a readily volatilizable liquid. The bulb 127 is preferably in the form of a coil to provide greater heat transfer surface.

The balance spring 108 is set to exert a pressure against the T-shaped lever 98 in an upward direction and against the force of the thermostatic bellows of the user control 66 and the room control 103. This arrangement balances stack temperature against room temperature, with the spring balance located in the back of the heater in a relatively low and cool location. The user control 66 has a limited range of adjustment from approximately 40° to 80° F. and has no springs or exposed moving parts to develop obvious troubles from soot or heat. The adjustment balance is set to permit the push rod 65 to move downwardly sufficiently in response to the warming up of the flue box 55 to close the snap action by-pass valve 59, the damper 121 being opened by additional downward movement of the push rod, this action being augmented by pressure developed in the room temperature bellows 103, as returning room air, passing over the bulb 127 at the base of the stove increases in temperature. Increased temperature of the returned room air builds up a gas pressure in the hermetically sealed

Liquid-filled bulb 127, and this is transmitted by the capillary tube 126 to the bellows 103.

As the room warms up and the stack temperature of the out-going gases is sufficiently warmed to insure safety, that is, sustained stove operation, the pressure in the thermostatic bellows 103 builds up and reduces the resistance on the push rod 65 as exerted by the spring 108, permitting the flue box bellows to open the check damper 121 sufficiently to divert air in part from the grate 20 and the ash pit 21 and allow it to pass directly into the flue box 55 through the opening 124. When the check valve 121 is held open by the push rod, the balance damper 30 takes over and feeds air through the ash pit 21 directly into the flue box. The valve 30 then acts as a barometrically controlled, back draft, check damper. This checking arrangement keeps objectionable gases from collecting in the ash pit, keeps the latter at a low temperature, removes cold air from lower floor levels and provides a quick correction of combustion conditions.

Basically, the controls provide a combination of operational regulation from three sources: First, draft pull; second, stack temperature; and, third, room temperature.

It will thus be seen that the present invention provides an improved heater for the burning of solid fuels. The magazine of the heater is formed so that it possesses fuel storage capacity, whereby to enable the heater to operate for prolonged periods of time without fuel replenishment. As the fuel descends toward the active zone of combustion, its temperature is progressively increased to liberate therefrom gases and volatiles which are efficiently consumed, so that little or no smoke is produced, particularly after combustion has been initiated.

In the initial combustion stages, the by-pass valve 59 is open so that any smoke which is generated at this period passes readily into the stack outlet or chimney, without gaining access to the atmosphere of the room in which the heater is positioned. After desired combustion has been initiated, the by-pass valve 59 is closed by the automatic actuation of the bellows of the thermostat unit 66. This enables the major part of the primary air entering the heater through the ash pit to pass directly through the grate structure into the burning fuel. The heater is designed to function efficiently on virtually all commercial grades of bituminous coal employed for house heating purposes and does not require the use of special fuels of selected sizes.

In introducing combustion air into the heater or stove, I utilize a combination of barometric dampers, indicated at 30, 38 and 48, operating on full draft pull or suction. These dampers cooperate with the thermostatically-actuated by-pass valve 59 to vary the calibration of the automatic balance control of said dampers, thereby increasing or decreasing the quantity and location of combustion air entering the fuel combustion zone. By the use of barometric dampers, the power required for their operation is very slight, as this type of damper is set on balance to operate normally on the suction of the draft. It will be noted that there are three levels of automatic supply for combustion air. Thus, when ashes are produced to an extent that they cover the primary air supply through the bottom grate, the draft burner will provide air through the center damper 38, which is separated from the lower damper 30 by a barrier wall.

Then, if additional air is needed, the draft burner opens the top draft or damper 48, thus assuring an adequate supply of air to sustain properly fuel combustion.

The draft pull mentioned above is controlled largely by the thermostatic unit 66, with its separate assembly on the back of the heater. Most of the controls are factory established, and the only control necessary for the user of the stove to operate is the knob 85 on the thermostatic unit. When the by-pass valve 59 is closed, the check damper 121 is used to regulate the heater operation. By the provision of the check valve or damper 121, air is taken from under the grate and by-passed to the waste gas outlet of the heater, thereby decreasing the volume of primary air supplied to the fuel and lowering the rate of fuel combustion.

My improved heater, as constructed, permits the use of high temperatures and smokeless and efficient combustion. In the high temperature regions, the burning fuel contacts with refractories capable of withstanding high temperatures. Beyond the high temperature zone, use is made of metals which are light in weight, provide for efficient heat transfer and which are not detrimentally affected by the heated gases contacting therewith, the entire structure being designed for compactness, lightness in weight and heating efficiency.

I claim:

1. A solid fuel-burning heater comprising: a casing structure having a base, outer vertical side walls and a vented top, said base including an ash pit having an air inlet, a grate at the top of said ash pit, a fire bowl arranged above and in registry with said grate, said bowl being open at its top and bottom and formed with orificed side walls, fuel inlet means passing through the top of said casing structure and disposed centrally of the latter for conducting fuel gravitationally to said bowl and grate, a horizontally extending refractory shield member arranged in said casing structure above and in spaced relation to said fire bowl and surrounding the lower end of said fuel inlet means, an inner vertical wall depending marginally from said shield member, said inner wall being positioned around said bowl in spaced relation therefrom to provide a chamber below said shield member and above said fire bowl, said chamber communicating with a passage formed around said bowl by said inner vertical wall for the downward flow of gaseous products of combustion released from the top of said bowl and delivered to said chamber and the upper part of said passage, an intermediate wall positioned between the outer vertical walls of said casing structure and said inner wall, said intermediate wall being spaced from said inner wall to provide a flue gas passage, means connecting said flue gas passage with said inner wall passage at the bottom of the latter, said flue gas passage being disposed for the upward flow of said products, means forming a gas chamber in the upper part of said casing structure by said inner and intermediate walls communicating with said flue gas passage there being a flue gas outlet leading from said flue gas chamber, said flue gas outlet being formed in one of the walls of said casing structure contiguous to the top thereof, said intermediate wall being spaced from the outer walls of said casing structure to form an air-heating passage open at the bottom thereof to the atmosphere and leading 75 through said casing structure from the base to

its vented top and adapted for the passage of atmospheric air in heat-receiving relationship with the outer surfaces of said intermediate wall, opening means establishing direct communication between the chamber below said shield member and the flue gas chamber, a bypass valve normally closing said opening means, and means responsive to the temperature of the gases traveling through said flue gas chamber for automatically operating said bypass valve.

2. A solid fuel-burning heater as defined in claim 1, and wherein said casing structure is formed internally with a divisional wall defining an air-conducting passage leading from the ash pit to the flue gas chamber independently of the inner and intermediate wall passages, and a damper valve positioned in said divisional wall, said damper valve functioning when open to admit of the flow of air from said ash pit into said flue gas chamber and diverting in part the flow of combustion air to said grate structure and fire bowl.

3. A heater for burning solid fuels, comprising a casing structure provided with an ash pit in the bottom thereof formed with an air inlet, a fire bowl open at its top and bottom and formed with air-admitting orifices in its side walls, a perforate grate arranged in the bottom of said fire bowl and providing for air flow from said ash pit into the bottom of the fire bowl, relatively spaced substantially vertically disposed inner, intermediate and outer walls forming elements of said casing structure, an air-conducting shell surrounding said fire bowl, and means including said inner wall forming an air inlet passage communicating with an opening in said intermediate wall and with said shell, a barometric valve normally closing said opening, a shield member supported by said inner wall above the open top of said fire bowl, to provide a chamber formed between the top of said fire bowl and said shield member within the confines of said inner wall for the reception and passage of gaseous products of combustion released from the top of said fire bowl, said chamber being in open communication with an initial downwardly extending fuel gas passage for such products, said initial passage being disposed between said shell and said inner wall, the spacing of said inner and intermediate walls being such as to provide a second fuel gas passage and means connecting said second passage with the bottom of said initial downwardly extending passage, said second passage being adapted for the upward flow of said products from the bottom of said initial passage and means forming a flue gas chamber formed in the upper part of said casing structure between said inner and intermediate walls and communicating with said second passage, said last-named chamber being in communication with a flue gas outlet provided in the outer walls of said casing structure, said intermediate and outer walls being relatively spaced to form an air-heating passage open at its lower end to the atmosphere and leading from the lower part of the casing structure to the top part thereof and adapted for the passage of atmospheric air in heat-exchanging relationship with the surfaces of said intermediate wall.

4. A heater utilizing solid fuels, comprising a casing structure including a base, outer vertical side walls and a vented top, said base being formed to provide an ash pit formed with an air inlet, a grate mounted in said casing structure above said ash pit for the passage of combustion

air drawn into said ash pit in an upward direction through the grate, a fire bowl arranged above and in registry with said grate for the reception of solid fuel, fuel-admitting means by which solid fuel is admitted into said fire bowl from the vented top of the casing structure, said bowl being open at its top and bottom and formed with air-admitting ports in the side walls thereof, substantially vertically disposed and relatively spaced inner and intermediate walls forming a part of said casing structure and disposed within the vertical side walls of the casing structure above said base, an air-supplying shell surrounding said fire bowl, means including said inner wall formed to provide an air-transmitting passage which communicates at one end with the interior of said shell and at its other end with an opening formed in said intermediate wall, there being an air-transmitting and heating passage formed between said intermediate wall and the vertical side walls of said casing structure, said last-named passage being in open communication with the atmosphere at the base of said casing structure and with the vented top thereof, a pivoted barometric damper governing the inflow of air through the opening provided in said intermediate wall for causing air flow through the passage leading to said shell, said inner and intermediate walls below said damper being formed to define another air passage leading from the air-conducting and heating space between the intermediate wall and one of said outer walls to said ash pit, a second barometric valve governing inflow of air from said air space between the intermediate and outer walls for transmission to said ash pit, a shield member supported by said inner wall above the top of said fire bowl and providing therebetween a chamber for the reception and passage of gaseous products of combustion released from the top of said fire bowl, the spacing of said inner and intermediate walls being such as to provide elongated passages for the transmission of said gaseous products of fuel combustion, said passages communicating openly with said shield member chamber a flue gas chamber means formed in the top of said casing structure between said inner and intermediate walls, said last-named passages communicating with said flue gas chamber means, and a bypass valve normally closing a bypass opening provided in said inner wall to establish direct gas flow communication between said shield member chamber and the flue gas chamber.

5. A heater utilizing solid fuels as defined in claim 4, and wherein means including said inner, intermediate and outer walls of the casing structure form a confined air-conducting passage which leads from said ash pit through a closeable opening to said flue gas chamber, whereby to conduct air directly from the ash pit of the casing structure to said flue gas chamber, and movable valve means normally arresting air flow through said closeable opening.

6. A solid fuel-burning heater comprising: a casing structure having a base, outer vertical side walls and a vented top, said base including an ash pit having an air inlet, a grate at the top of said ash pit, a fire bowl arranged above and in registry with said grate, said bowl being open at its top and bottom and formed with orificed side walls, fuel inlet means passing through the top of said casing structure and disposed centrally of the latter for conducting fuel gravitationally to said bowl and grate, a horizontally extending

refractory shield member arranged in said casing structure above and in spaced relation to said fire bowl and surrounding the lower end of said fuel inlet means, an inner vertical wall depending marginally from said shield member, said inner wall being positioned around said bowl in spaced relation therefrom to provide a chamber below said shield member and above said fire bowl, said chamber communicating with a passage formed around said bowl by said inner vertical wall for the downward flow of gaseous products of combustion released from the top of said bowl and delivered to said chamber and the upper part of said passage, an intermediate wall positioned between the outer vertical walls of said casing structure and said inner wall, said intermediate wall being spaced from said inner wall to provide a flue gas passage, means connecting said flue gas passage with said inner wall passage at the bottom of the latter, said flue gas passage being disposed for the upward flow of said products, means forming a gas chamber in the upper part of said casing structure by said inner and intermediate walls, communicating with said flue gas passage there being a flue gas outlet leading from said flue gas chamber, said flue gas outlet being formed in one of the walls of said casing structure contiguous to the top thereof, said intermediate wall being spaced from the outer walls of said casing structure to form an air-heating passage open at the bottom thereof to the atmosphere and leading through said casing structure from the base to its vented top and adapted for the passage of atmospheric air in heat-receiving relationship with the outer surfaces of said intermediate wall, opening means establishing direct communication between the chamber below said shield member and the flue gas chamber, a bypass valve normally closing said

opening means, means responsive to the temperature of the gases traveling through said flue gas chamber for automatically operating said bypass valve, a divisional wall formed internally of said casing structure, said divisional wall defining an air-conducting passage leading from the ash pit to the flue gas chamber independently of the inner and intermediate wall passages, a damper valve positioned in said divisional wall, said damper valve serving when open to provide for the flow of air from said ash pit into said flue gas chamber and diverting in part the flow of combustion air to said grate structure and fire bowl, and means cooperative with the temperature-responsive means for opening and closing the bypass valve for effecting opening operation on the part of the damper valve.
